Primary Examiner — Richelle G Shelton(57) **CLAIM**

The ornamental design for an earplug tip, as shown and described.

DESCRIPTION

FIG. 1 is a perspective view showing the new design for an earplug tip.

FIG. 2 is a front view thereof, the rear view, left view and right view being identical thereto;

FIG. 3 is a top view thereof;

FIG. 4 is a bottom view thereof; and,

FIG. 5 is a cross-sectional view taken at line 5-5 of FIG. 3. The long and short dashed broken line shown represents the bounds of the claimed design while all other broken lines are included for the purpose of illustrating environmental structure. The broken lines and the unshaded surfaces within form no part of the claimed design. Any shading is provided to illustrate contour only and is not an indication of surface texture.
